H. TOBLER.

ELECTROLYTIC APPARATUS.

APPLICATION FILED JUNE 19, 1918. RENEWED JULY 29, 1920.

Patented June 7, 1921.

UNITED STATES PATENT OFFICE.

HENRI TOBLER, OF HACKENSACK, NEW JERSEY, ASSIGNOR TO AMERICAN BROMINE COMPANY, OF MAYWOOD, NEW JERSEY, A CORPORATION OF NEW JERSEY.

ELECTROLYTIC APPARATUS.

1,380,852.

Specification of Letters Patent. Patented June 7, 1921.

Application filed June 19, 1918, Serial No. 240,781. Renewed July 29, 1920. Serial No. 399,883.

To all whom it may concern:

Be it known that I, HENRI TOBLER, a citizen of the United States, residing at Hackensack, in the county of Bergen, State of New Jersey, have invented certain new and useful Improvements in Electrolytic Apparatus; and I do hereby declare the following to be a full, clear, and exact description of the invention, such as will enable others skilled in the art to which it appertains to make and use the same.

The electrolytic apparatus of the present invention is of use for the electrolysis of brine, as for the production of hypochlorites, and is particularly suitable for use on natural brines, such as those of Michigan and the Ohio River valley, when bromin or other halogen is to be recovered from the brine by electrolytic oxidation, followed by known methods of separation, purification and absorption.

The apparatus is such that if bromin alone is the desired halogen, electrolysis can be conducted in such a manner that there will be a minimum of chlorin simultaneously set free from its compounds in the brine.

The apparatus is of simple and cheap construction; the electrical elements are effectively insulated, the brine containers and conduits are not subject to quick deterioration and are well protected against leakage, and such electrodes and other elements as are subject to wear or corrosion can be easily renewed with but slight interruption in the operation.

In the accompanying drawing, which is to some extent diagrammatic, one embodiment of the apparatus is illustrated as comprising a series of containers, each adapted to serve as cathode of an electrolytic cell, and each provided with a carbon anode, preferably concentric with the container, and between which and the container, the brine to be electrolyzed is circulated. Pipes or conduits of non-conducting material form tortuous paths from one container to the next, so that the brine undergoes progressive electrolysis in the several units or cells of the apparatus. The number of cells thus connected together in series can be proportioned to the voltage of the electrical energy conveniently available; but for a 115 to 125 volt direct current supply I prefer to use 24 cells thus connected in series. The quantity of cur-

rent is, of course, proportioned to the degree of electrolysis or oxidation desired and for the liberation of bromin from chemical union in natural brines, I prefer to use a current density which will over-electrolyze the brine so far as concerns its bromin content, or in other words, will yield some free chlorin together with substantially all of the bromin.

Each unit or cell of the electrolytic apparatus illustrated in the accompanying drawing as the preferred embodiment, comprises a container 1 which preferably is of tubular shape, and vertically disposed. The main part of this container may consist of wrought iron pipe but preferably is of cast iron and terminates at the bottom in a fitting 2, the lower open end of which is provided with a threaded bushing 3 of hard rubber or the like, into which is threaded or otherwise suitably secured, an anode 4 of carbon, preferably graphitic carbon, and of cylindrical shape. There is therefore left between the cylindrical anode and the metal container which is to serve as cathode, a vertical, annular space through which brine can be circulated in a desired direction and can be electrolyzed by current of suitable voltage passing from anode to cathode through the brine.

Each metal container is surmounted by a T-fitting 5 of tile or like insulating material, preferably a calked bell-joint 6 being used between the tile fitting and the metal container to insure a fluid-tight connection which can be taken apart in case the apparatus is to be repaired. The tile fitting for the first container of the series is equipped with an inlet conduit 7 through which the raw brine is supplied to the apparatus. This conduit has an upward bend to insure a brine level well above all metal parts of the apparatus, as, for instance, at the level indicated on the drawing.

Connected to the bottom fitting 2 by a nipple 8 is a cast iron T-coupling 9, the lower end of which is closed by a clean-out plug 10 and the upper end of which is connected by a socket member 11 with a pipe or conduit 12 of insulating material, which, by means of an elbow 13, communicates with the inlet opening of the next tile fitting 5, thereby forming a tortuous path for brine from the bottom of one container to the top of

the next. This insures free circulation of the brine throughout the series of electrolytic cells but limits to a negligible amount the leakage of electrical energy from one 5 anode to more remote cathodes of the series.

Each carbon anode is provided with a binding post 14 to which is attached a cable 15, by which the electric current is supplied to the anode; and each T-fitting 9 is provided with a binding post 16, to which one 10 of these cables 15 is connected, so that direct current entering the first anode 4 from the dynamo or other source of electrical energy passes through the brine to the metal container 15 of the cell and then out through cable 15 to the next anode, and so on throughout the entire series.

The chemical effect of electrolysis on a natural bromin containing brine is first to 20 liberate the bromin from its chemical combinations in the brine, and second to liberate the chlorin from its chemical combinations, the voltage of decomposition being somewhat higher for chlorids than for 25 bromids. The freed bromin remains for the most part mechanically dissolved in the brine, and the free chlorin will chemically react on any unreduced bromids in the brine, to liberate an equivalent quantity of free 30 bromin. Consequently, in the electrolysis of a natural brine in this apparatus, some of the resulting free bromin may come from electrolysis directly, and some may come as a secondary product resulting 35 from the electrolysis of chlorids. The apparatus is so designed as to be especially conducive to this secondary action, in that any bubbles of chlorin liberated on the anode must pass upward through a considerable column of downwardly moving 40 brine before they can escape at the surface of the brine. There is, therefore, good opportunity for intimate contact between the chlorin and the brine, and much of the chlorin, therefore is used in desirable manner, 45 when freed bromin is the ultimate product.

However, the current density used may be such as to liberate some free chlorin, and even some free bromin at the top of each 50 column of brine. I therefore provide means for absorbing these escaping halogens. In the preferred embodiment, I use a halogen absorbent liquid, such as an oil of suitable character and preferably I circulate this liquid through the cells in series 55 to take up the halogens, recovering them again from the liquid in the form of bromids and chlorids, as hereinafter explained.

To this end, each tile fitting 5 is 60 mounted by a tile fitting 17, as shown, and the tile fittings 17 are connected together by tile pipes 18 to form a conduit leading to a pump 19, whereby the absorbent oil may be recirculated through the entire system.

From time to time, this oil may be drawn 65 off, as through a by-pass 20, for chemical or other treatment to restore its absorbent qualities and to recover its halogen content. The top of each fitting 17 may be open to the air or, if desired, may be connected up 70 to conserve the hydrogen and such other gases as may escape absorption by the oil.

The absorbent liquid which I prefer, is made as follows:

I collect those portions of a crude oil of 75 the Pennsylvania type which distil between 110° and 160° C., or I distil this fraction from a gasoline obtained from such a crude, but without the use of a cracking or other process which would increase the amounts 80 of unsaturated hydro-carbons in the fraction. This fraction, if obtained from a proper source, will contain generally less than one per cent. of unsaturated hydrocarbons, and as these are undesirable, they 85 are disposed of by direct saturation with bromin, during which operation a small amount of hydrobromic acid is formed. The oil is then washed by agitation with a 10% 90 solution of caustic soda, whereby the hydrobromic acid is recovered and some resinous matters contained in the oil are eliminated. The oil is then ready for use in the apparatus illustrated in the drawing. Such a 95 saturated and purified hydrocarbon will readily dissolve bromin and chlorin. A partial combination may take place, but the reaction is very slow, especially if the solution be kept in darkness. The halogen thus absorbed by the oil may be removed 100 therefrom by agitating the hydrocarbon with an alkali, whereupon the alkali will combine with the bromin and chlorin, forming the corresponding bromids and bromates and chlorids and chlorates. The oil is then ready 105 for further use as an absorbent.

I am aware that the form of the apparatus and its method of use may be varied in many particulars, and I contemplate such variations as reasonably come within the 110 spirit of my invention as above described and as defined by the claims appended hereto.

I claim:

1. Electrolytic apparatus comprising a 115 series of metal containers adapted to serve as cathodes at different electrical potentials, means for circulating brine by a tortuous path from one container to another, and a carbon anode positioned in each container 120 and about which said brine circulates during electrolysis, substantially as described.

2. Electrolytic apparatus comprising a series of tubular iron containers adapted to serve as cathodes at different electrical potentials, means for circulating brine by a tortuous path from one container to another, 125 and a cylindrical carbon anode centrally po-

sitioned in each container and about which said brine circulates during electrolysis, substantially as described.

3. Electrolytic apparatus comprising a series of vertical containers adapted to serve as cathodes at different electrical potentials, means for circulating brine by a tortuous path from one container to another, and an anode positioned in each container and about which said brine circulates during electrolysis, substantially as described.

4. Electrolytic apparatus comprising a series of vertical containers adapted to serve as cathodes, means for circulating brine by a tortuous path from the lower part of one container into the upper part of the next container, and a carbon anode positioned in each container and about which said brine circulates during electrolysis, substantially as described.

5. Electrolytic apparatus comprising a series of iron containers adapted to serve as cathodes at different electrical potentials, an insulating bushing at the bottom of each container, a carbon anode mounted in each bushing and about which brine may be circulated, and an insulating pipe connecting the lower part of one container with the upper part of the next container to serve as a tortuous path for the circulation of brine and a clean-out opening near the base of each container, substantially as described.

6. Electrolytic apparatus comprising a series of metal containers adapted to serve as cathodes, an insulating fitting surmounting each container, an insulating pipe for circulating brine by a tortuous path from the lower part of one container into the insulating fitting which surmounts the next container, a carbon electrode in each container to form therewith an electrolytic cell, and means electrically connecting said cells

in series to progressively electrolyze the brine as it passes through the series of containers.

7. Electrolytic apparatus comprising a plurality of vertical containers adapted to serve as cathodes in an electrical series, means for circulating brine by a tortuous path from one container to another; an anode positioned in each container about which said brine circulates during electrolysis, and gas absorbing means above the brine in each container, substantially as described.

8. Electrolytic apparatus comprising a plurality of vertical containers adapted to serve as cathodes, means for circulating brine from one container to another, an anode positioned in each container and about which said brine circulates during electrolysis, and a halogen absorbing oil above the column of brine in each vertical container, substantially as described.

9. Electrolytic apparatus comprising a series of electrolytic cells through which a brine may be circulated to undergo progressive electrolysis, and means for maintaining a halogen absorbing liquid over the circulating brine but non-miscible therewith, substantially as described.

10. Electrolytic apparatus comprising a series of tubular iron containers adapted to serve as cathodes, means for circulating brine by a tortuous path from one container to another, a carbon anode centrally positioned in each container and about which said brine circulates during electrolysis, and means for circulating a halogen absorbing oil over the brine in said containers, substantially as described.

In testimony whereof I affix my signature.

HENRI TOBLER.
